UNITED STATES PATENT OFFICE.

SAMUEL R. SHOUP, OF WEEHAWKEN, NEW JERSEY.

LATH BOARD.

Application filed January 4, 1921. Serial No. 435,007.

To all whom it may concern:

Be it known that I, SAMUEL R. SHOUP, a citizen of the United States, residing in Weehawken, New Jersey, have invented a certain Lath Board, of which the following is a specification.

This invention relates to a manufactured product; a wired lath board, and more particularly to laths or heavier strips of wood fastened together with wire and mounted on heavy tarred paper. The lath board is intended to be nailed on to the studding frames and joists of new buildings and to the walls of old buildings. It has several desirable features;—it is the support and backing for concrete, plaster or veneer. The tarred paper backing keeps the house dry and tight; the paper also acts as a backing, thus preventing the waste of concrete; the bevelled edges allow the concrete to lock itself into place; the laths fastened together with wire make the material strong and substantial. The lath board is much easier and quicker to apply and nail in place than individual laths.

The wired lath board may be made of strips of wood much heavier than the common lath. This board nailed to the joist becomes an excellent backing for concrete floors. It also makes splendid material for packing cases.

Laths spaced apart and adapted to hold concrete are arranged parallel to each other and are bound by pairs of parallel wires; at an angle to the binding wires the laths are cemented to a sheet of tarred paper diagonal to the length of sheet, the line of the binding wires being parallel to the edge of the sheet as shown in Fig. 3. This angular arrangement of laths is nailed to the studding of buildings and used as a brace the same as and in place of the sheathing boards as now used.

My invention is fully shown in the accompanying drawings.

Fig. 1 is a plan view of a small piece of my improved lath board.

Fig. 2 is an end section of the above.

Figure 3 is a plan view showing the laths wire-bound and mounted on weather proof-

ing paper at an angle to the binding wires and to the web of paper.

Fig. 4 is an end view of same.

In the drawings wood strips or laths (Fig. 1 No. 10) are shown equally spaced, 55 bevelled on one or both edges and bound together by iron wire or heavy twine (11 and 12).

Four pair of binding wires (13, 14, 15 and 16) bind the laths and hold them securely. When desired the bound laths are wound into rolls and sold without the tar paper back.

Paper (17) coming from a roll is coated with a thin layer of hot tar (18); the bound laths are pressed to the hot tar on the paper and wound into a tight roll; the tar quickly cools and the lath board is ready for use.

Having thus described my invention, I claim and desire to secure by Letters Patent:

1. In combination a series of wooden strips arranged parallel to each other, several pairs of transverse wires securing said strips together, each of said pairs of wires 75 being twisted together between each of said wooden strips, and a sheet of weather proofing paper cemented to the said wooden strips.

2. In combination a series of wooden strips arranged parallel to each other, several pairs of diagonal wires securing said strips together, each of said pairs of wires being twisted together between each of said wooden strips, and a sheet of weather proofing paper cemented to the said wooden strips.

3. In combination a series of wooden strips having bevelled edges adapted to hold concrete arranged parallel to each other, 90 several pairs of diagonal wires securing said strips together, each of said pairs of wires being twisted together between each of said wooden strips, and a sheet of weather proofing paper cemented to the said wooden 95 strips.

4. In building material as described a series of sawed wood strips having bevelled edges adapted to hold concrete, arranged parallel to each other and connected to 100

gether by means of pairs of binding wires twisted together between each pair of wood strips; the said binding wires crossing each strip diagonally, thus binding the strips 5 diagonally, to the binding wires, together with a sheet of weather-proof material cemented to the back of the said sawed strips.

In testimony whereof, I have signed my name to this specification in the presence of two subscribing witnesses.

SAMUEL R. SHOUP.
